US0D1102136S

(12) **United States Design Patent** (10) **Patent No.:** **US D1,102,136 S**
(45) **Date of Patent:** **** Nov. 18, 2025**

(54) **BATTERY**

(71) Applicant: **Qingdao Activa Shade Inc.**, Qingdao (CN)

(72) Inventor: **Zhun-An Ma**, Ningbo (CN)

(73) Assignee: **Qingdao Activa Shade Inc.**, Qingdao (CN)

(**) Term: **15 Years**

(21) Appl. No.: **29/962,341**

(22) Filed: **Sep. 11, 2024**

Related U.S. Application Data

(63) Continuation of application No. 29/866,084, filed on Aug. 26, 2022, now Pat. No. Des. 1,047,411.

(51) **LOC (15) Cl.** **03-03**

CLAIM

The ornamental design for a battery as shown and described.

DESCRIPTION

FIG. 1 shows a battery embodying the new design thereof, shown in the context of an umbrella.

FIG. 2 is a perspective view of the umbrella hub design illustrated in FIG. 1 in dash, and a battery shown.

FIG. 3 shows a perspective view of the battery illustrated in FIG. 1, the battery useable with the umbrella hub design of FIG. 2.

FIG. 4 is a front view of the battery design of FIG. 3.

FIG. 5 is a back view of the battery design of FIG. 3.

FIG. 6 is a first side view of the battery design of FIG. 3.

FIG. 7 is a second side view of the battery design of FIG. 3.

FIG. 8 is a top view of the battery design of FIG. 3; and,

FIG. 9 is a bottom view of the battery design of FIG. 3.

All features in broken lines are for the purpose of illustrating environmental structure and form no part of the claimed subject matter.

1 Claim, 6 Drawing Sheets
